TOOL FOR ELECTRIC-LAMP SOCKETS.

No. 908,408.

Specification of Letters Patent.

Patented Dec. 8, 1903.

Application filed May 28, 1903. Serial No. 435,437.

To all whom it may concern:

Be it known that I, GILBERT W. GOODRIDGE, a citizen of the United States of America, and a resident of the city of Bridgeport, in the county of Fairfield, in the State of Connecticut, have invented a certain new and useful Improved Tool for Electric - Lamp Sockets, of which the following is a specification.

10 My invention consists of an improved tool for use in fitting electric lamp sockets in place upon fixtures or other supports, the tool being more especially useful where sockets are to be introduced within ornamental fittings or "husks."

In the accompanying drawings Figure 1 is a side elevation showing the tool about to have its operating head introduced into a cap C; Fig. 2 is a corresponding view showing the 20 tool in place; Fig. 3 is an end view of the tool head; Fig. 4 is a sectional view of the tool carrying a socket shell.

The tool comprises a head A and handle A¹, with cross-piece a, and a hole a¹ is formed 25 through the tool head and handle for a purpose explained hereinafter.

The head of the tool is preferably made of the circular outline shown to fit the interior of the flanged part of a socket cap, and a 30 number of lateral projections p, p, are formed on the tool head to engage openings or recesses in the flange of the socket cap. In the present instance I have shown the tool as especially constructed for use in connection 35 with the electric lamp socket forming the subject of my Patent No. 872,283, dated November 26th, 1907, and in which the flange of the cap is uniformly wrinkled or corrugated, and accordingly the periphery of 40 the tool head is formed with projections p spaced to correspond with and fit into the recesses formed by the corrugations c in the flange of the cap C.

When the tool head is inserted in the cap, 45 the two are locked together rotarily, so that the wire man can readily insert the cap into the bottom of an ornamental husk and screw it up on the threaded pipe end by means of the tool. The wires projecting from the pipe 50 end may be received into the hole a¹ formed

in the head and handle of the tool, and therefore twisting of the wires will be avoided in screwing up the cap.

I prefer to form the head of the tool deeper than the flange of the cap and to form marks 55 m on this rear extension in line with the projections p, in order that when the wireman is giving the last turn to the cap on the pipe he may stop with one of these lines n opposite the center line of the slot left in the husk 60 for the reception of the key of the socket. Then in putting the socket shell and contents into the cap, the wireman will know that the key will be in line, as it should be, with one of the corrugations c in the cap, and the socket 65 will pass that much more directly and easily into the cap, and the latching means will at once snap into engagement.

I recess out the front end¹ of the tool head, as indicated at a² in Fig. 4 to receive the outer 70 end of the shell S and the projecting end of the insulating lining x, when the bead s of the shell comes to rest on the annular shoulder or flange y thus formed in the end of the tool head, so that the thrust needed to push the 75 shell into the cap after the latter has been screwed onto the pipe within a husk may thus be taken by the shell S, instead of by the end of the lining, as would be apt to be the case if the shell were put in by hand. Pressure 80 applied to the front end of the lining will mar its appearance and will also force the lining to project at the back of the shell and interfere with the fitting of the shell into the cap.

I claim as my invention—

1. A tool for electric lamp sockets, comprising a handle and a head with a hole through the head for the wires, the head adapted to fit into a socket cap and having parts to engage the cap rotarily.

2. A tool for electric lamp sockets, comprising a handle and a circular head to fit within and rotarily engage the flange of a socket cap, and also recessed out at its front end to receive the outer end of a socket shell 95 with the bead of the latter resting on the head, as and for the purpose described.

3. A tool for an electric lamp socket, comprising a handle and a head with a hole through the head and handle for the wires, 100

the head being adapted to fit within the socket cap and having parts to engage recesses or notches in the cap.

4. A tool for an electric lamp socket, comprising a handle and a circular head externally corrugated to fit within the corrugated flange of a socket cap.

In testimony whereof I have signed my name to this specification, in the presence of two subscribing witnesses.

GILBERT W. GOODRIDGE
